TRANSPARENT HAT BOX

Lynde De F. Hokerk, Utica, N. Y., assignor to
 Kerk Guild, Inc., Whitesboro, N. Y., a corpora-
 tion of New York

Application March 10, 1937, Serial No. 130,199

3 Claims. (CL 229—5.7)

This invention relates to containers for hats and other articles.

In households in particular, men and women very often store the hats not being worn in pasteboard and other boxes having a removable lid or cover. Frequently, the lids or covers of several boxes are removed before the particular hat desired is obtained, unless there be some designation on the box as to the nature of the hat contained therein. The same practice is sometimes followed in stores. These hat boxes or containers are generally composed of pasteboard or otherwise constructed so that the contents of the boxes or containers are not observable without removing the lid or cover of the box or container, unless, as stated, there is some designation on the box or container as to the nature of the particular hat contained or stored therein. This method of access to the hat or other article desired consumes time, and it is the primary object of the present invention to provide a practical, efficient container or receptacle for storing hats or other articles embodying a transparent wall through which the hat or other article may be easily seen and identified without removal of the lid or cover of the container, or for the convenience of the user in selecting the particular hat or other article desired among a series of receptacles, containers or boxes.

Another object of the invention resides in the provision of a box or container provided with a transparent wall formed of a thin gauge material which is so reenforced as to provide the necessary strength and durability required of a box or container of the nature stated and which will successfully withstand repeated handling over a considerable period of time.

A still further object of the invention is to provide a container or box of the nature stated, and of round, cylindrical or any other suitable shape, in which the side wall of the box is composed of transparent material such as thin cellulose or other suitable material which has its ends so joined to the remaining portions of the members of the container or box as to be permitted to have a limited relative movement for taking care of the normal unequal expansion and contraction of these materials and in such a manner as to avoid wrinkling or distortion of the transparent side wall of the box or container.

It is still further designed to provide a container or box for hats or other articles having a transparent side wall whose upper cover-receiving edge is covered and reenforced in a manner to preserve its shape, impart strength to the side

wall as a whole and to avoid the danger of splitting of the material thereof.

With the above and other objects in view, the invention consists in the construction and novel combination and arrangement of parts herein-after fully described, illustrated in the accompanying drawing and pointed out in the claims hereto appended, it being understood that various changes in the form, proportion and minor details of construction, within the scope of the 10 claims, may be resorted to without departing from the spirit or sacrificing any of the advantages of the invention.

Figure 1 is a side elevation of the improved receptacle of this invention. 15

Figure 2 is a horizontal sectional view taken centrally therethrough.

Figure 3 is an enlarged vertical sectional view through one side thereof.

Figure 4 is a fragmentary side view of a portion of the upper edge of the box wall, and 20

Figure 5 is a similar view of a portion of the bottom edge of the wall, with the inner expanding band removed.

Referring now to these figures, and particularly to Figures 1 and 2, the invention proposes a receptacle in the nature of a box for the protection or storage of hats and like articles. In the particular form and embodiment as shown, the box includes a circular bottom 10 and a 30 similarly-shaped cover or lid 11, the former having an upstanding annular flange 12 and the latter a depending flange 13. Each of these parts may be formed of various materials, though fibre or the commonly employed cardboard is 35 preferable.

The wall 14 of the box is constituted by a single section of a suitable transparent material such as Cellulose, which, by reason of certain features to be presently described, may be of thin 40 gauge, say, .020 inch, so that the contents of the box will be plainly visible and a pleasing appearance is presented. This section of material is shown with circumferentially overlapping end portions 15 which are suitably joined, as by 45 means of a transparent adhesive, so that a cylindrical wall is thus formed with a vertical reenforcing seam and of a size to be telescoped at its upper edge by the flange 13 of the cover 11, and to telescope at its lower edge within the flange 50 12 of the box bottom 10.

Around and within the upper edge of the transparent wall 14 is a cardboard or other re-enforcing band 16 so placed that its upper edge 55 is flush with the upper edge of the wall to permit

of embracing and covering both said edges by means of a leather, fabric or other flexible binding tape or edging 17. This tape or edging 17 may be secured to the reenforcing band 16 and the upper edge of the wall 14 by a suitable adhesive or, as shown, by stitches 18 through these parts along a line paralleling the upper edge of the wall. The upper edge of the wall is thus firmly reenforced and held to proper shape for the reception of the flanged cover 11.

The lower edge of wall 14, which, as above stated, telescopes within the bottom flange 12, is, for the reasons previously set forth, provided at spaced points therearound with openings 19 as seen in Figures 3 and 5, and through these openings the prongs 20 of metallic fastening members 21 are forced into the inner surface of the bottom flange 12 to thus anchor the fastening members 21 so that by their abutting engagement with the inner surface of wall 14 they confine the latter at spaced points against displacement and at the same time allow for a limited movement of the wall circumferentially of the box bottom. This permissible limited relative movement is sufficient to take care of the relatively greater coefficient of expansion of the wall 14 with respect to that of the bottom 10 and its flange 12 so as to avoid wrinkling of the former under climatic changes.

Since the above fastening means engage the wall at circumferentially spaced points, an inner expanding and reenforcing band 22 is employed to yieldingly bear against and hold the lower edge of wall 14 in contact with the bottom flange 12 uniformly therearound. This band 22, like the upper reenforcing band 16, may be made of cardboard or other suitable material, and is preferably secured to the inner surface of wall 14 by a suitable adhesive.

Thus the wall 14, formed as previously described, is effectively reenforced at its upper and lower edges, and these reenforcements, cooperating with its overlapping connected ends 15, form a support which is sufficiently effective to justify the use of very thin transparent material, without in any way detracting from the pleasing appearance of the box as a whole.

It will be understood that the side wall of the container or box is preferably continuous so that

the contained article may be viewed from any part of the side wall and it will also be understood that the contour of the box, instead of being round as shown, may be square, hexagonal or any other suitable shape.

What is claimed is:

1. A protecting or storing container for hats and other articles comprising a body and a cover or lid, the said body including a flanged bottom, a transparent flexible wall whose lower flexible edge telescopes within the bottom flange, means connecting the lower edge of the wall at spaced points therearound and at the same time allowing limited relative movement of the wall, and an expander within and around the said connected edge of the transparent wall for yieldably pressing the latter into firm uniform contact with the flange of the bottom.

2. A protecting or storing container for hats and other articles comprising a body and a cover or lid, the said body including a flanged bottom, a transparent flexible wall having an upper reinforced edge to receive the cover and having its lower edge telescoping within the flange of the bottom and provided with openings at spaced points therearound, fastening members abutting the said lower edge of the wall and engaging the bottom flange through said openings to permit limited movement of the wall relative to said flange, and means for reenforcing the said lower connected edge of the wall and uniformly holding the same yieldably against the flange continuously along the latter.

3. A container of the character set forth comprising a flanged bottom, a flanged cover, a wall of thin flexible material extending continuously from said bottom to said cover and consisting of a single piece of transparent material having overlapping connected ends, disposed with its lower edge within the flanged bottom, wall holding members holding the lower annular edge of the transparent wall against the bottom flange, said members being in movable engagement with the said lower edge of the wall to permit circumferential creeping of the latter and thus compensate for expansion and contraction thereof relative to the flanged bottom.
